CLAIM

The ornamental design for the cleated sole for athletic shoe, as shown and described.

DESCRIPTION

FIG. 1 is a bottom plan view of a cleated sole for an athletic shoe showing my new design;
FIG. 2 is an inverted left side elevational view thereof;
FIG. 3 is a top plan view thereof;
FIG. 4 is a right side elevational view of FIG. 3;
FIG. 5 is a front elevational view thereof;
FIG. 6 is a rear elevational view thereof;
FIG. 7 is a top plan view of another embodiment of my new design of FIGS. 1-6;
FIG. 8 is a right side elevational view thereof;
FIG. 9 is a left side elevational view thereof;
FIG. 10 is an inverted front elevational view thereof;
FIG. 11 is an inverted rear elevational view thereof.

FIG. 1.

FIG. 2.

FIG. 3.

FIG. 4.

FIG. 5.

FIG. 6.

FIG. 7.

FIG. 8.

FIG. 9.

FIG. 10.

FIG. 11.
